UNITED STATES PATENT OFFICE.

WILHO A. KOSKEN, OF BOSTON, MASSACHUSETTS, ASSIGNOR, BY MESNE ASSIGNMENTS, TO BENJAMIN FARNHAM SMITH, OF CONCORD, MASSACHUSETTS.

RING TRAVELER.

Application filed November 8, 1922. Serial No. 599,638.

To all whom it may concern:

Be it known that I, Wilho A. Kosken, a citizen of the Republic of Finland, residing at Boston, in the county of Suffolk and 5 State of Massachusetts, have invented new and useful Improvements in Ring Travelers, of which the following is a specification.

This invention relates to ring travelers for use in the spinning or twisting of yarns.

10 As heretofore constructed such rings have been made as light as possible and yarns have been made to pass through a thread eye extending upwardly from the ring. With this construction various attempts 15 have been made to balance the weight of the ring and eye so as to cause the ring to run as true as possible.

The present invention provides a construction of ring designed from an entirely 20 different standpoint, the weight of the ring being very considerable so that the weight of the eye is a very small factor and may for all practical purposes be neglected. Means for supporting the ring so that it 25 may be started to rotate by a slight tension of the yarn insufficient to cause breakage of weak yarns is also provided, this means, however, acting when the ring is rotating at high speed to impart a sufficient drag to 30 effect proper twisting, provision also being made to superpose an additional adjustable drag needed for properly twisting heavier and stronger yarns.

Much trouble has been experienced with 35 light rings from the flying of oil used for lubrication, this oil striking the yarn, so as to necessitate frequent cleaning. The light rings also have been liable to damage resulting from frictional heat produced in 40 the rapid rotation and they are also liable to be pulled out of position by sudden strains exerted thereon during operation.

In the construction of the present invention no trouble is experienced from spattering 45 of oil on the yarns and as the ring is of considerable weight it is not injuriously effected by any heat which may be produced nor can it be pulled out of position by sudden stress exerted thereon.

50 The invention further contemplates an improved construction of yarn eye which lies entirely within the periphery of the ring instead of extending upwardly therefrom as in the former construction. The eye is 55 placed where it is not liable to cause injury

to the operator's fingers when in operation, and it is formed so that it can be readily threaded and so that there is no danger of the yarns escaping therethrough during 60 operation.

Further objects and advantageous details and combination of parts will appear from a more complete description of certain embodiments of the invention disclosed in the accompanying drawings in which 65

Figure 1 is a top plan of the traveler and its mounting.

Figure 2 is a side elevation thereof partly broken away.

Figures 3 and 4 are detail sections on 70 lines 3—3 and 4—4, respectively, of Figure 1.

Figure 5 is a partial elevation of the inside of the ring showing the yarn eye.

Figures 6 and 7 are a fragmentary plan 75 and elevation, respectively, showing a modified construction of brake.

Figure 8 is a fragmentary view similar to a portion of Figure 6 but illustrating a further modification.

Referring to Figures 1, 2, and 3, at 1 is 80 indicated a ring shaped support having outwardly extending lugs 2. Each of these lugs is perforated as at 3 to form a recess for the reception of an oil cup 4, the upper end of which extends considerably above 85 the upper face of the support 1. Fixed to the upper faces of the lugs 2 are bearing supports or holders 5, each of which extends over a socket or perforation 3 and in axial alinement with which is a bore 6. 90

Seated in this bore is the upper end of a hollow pin or shaft 7, the lower end of which extends within a short distance from the bottom of the oil cup 4. The shaft 7 may be fixed in position in the support 5 95 by means of a set screw 8 threaded in the support and having a reduced extremity 9 engaging a perforation in the shaft. Journaled on each shaft 7 is a traveler supporting bearing comprising a pulley or roller 100 10 having upper and lower flanges 11 and 12 and an extended hub portion 13 which projects considerably below the lower flange 12 and to the lower end of the shaft 7 when

the roller is in position. The upper edge 105 of the cup 4 which surrounds the hub projects upwardly between this hub and an annular portion 14 of the roller from which projects the flange 12 as shown in Figure 3 so as to be partially enclosed by its periph- 110

ery. Lubricant, such as a heavy oil or grease, may be placed in the cup 4 through the axial opening 15 of the shaft 7, the upper end of which may be closed off to prevent the access of dirt thereto by any suitable means such as the plug 16 having a split shank portion 17 resiliently engaging the sides of the opening. During the rotation of the roller, as will be later described, lubricant from the cup, which may be filled to the level indicated at 17^a, finds its way between the surface of the shaft 6 and the hub 13, by capillary attraction, and then flows out between the flange 11 and the portion 18 of the supporting bracket with which it contacts. It is important that a heavy lubricant such as heavy oil or grease shall be used, otherwise the lubricant finding its way to the top of the roller is apt to be thrown out by centrifugal force from beneath the engaging portion 18 of the supporting bracket.

Between the flanges 11 and 12 of the various rollers is supported in the same plane therewith and engaging their peripheral faces the ring traveler indicated at 20. This traveler is of substantial weight, a traveler five inches in diameter weighing approximately a half a pound. As shown three supporting rollers 10 are employed equi-distantly spaced angularly about the periphery of the ring traveler 20 and furnish the sole support therefor. It will be noted that the rollers 10 are of considerably smaller diameter than the ring traveler. They therefore act to permit rotation of the ring traveler to be initiated readily but when the ring traveler is up to speed, the five inch traveler rotating, say, 1500 R. P. M., the extremely high peripheral speed of the comparatively large ring can not be attained by the small diameter rollers 10 since this would require an extremely high angular velocity for these rollers which it is impossible for them to reach. They therefore impart a frictional drag to the rotation of the traveler at this high speed which imparts a tension to the yarns so as to cause proper twisting thereof, the parts being preferably so designed and proportioned that the retarding effect from this cause is sufficient for the lighter and weaker yarns. Adjacent each roller 10 the upper face of the support 1 is formed with an arcuate groove 21 for the reception of dirt or other foreign matter which may be removed from the ring by the action of the rollers thereon. This groove 21 communicates with a downwardly inclined passage 22 which extends on either side of the oil cup 4 and opens outwardly of the lug 2 as at 23, thus furnishing an escape for such foreign matter outwardly of the ring support.

For working on heavier yarns where a heavier tension must be employed, provision

is made for imparting an additional drag to the rotation of the traveler. One form of this mechanism is illustrated in Figures 1, 2, and 4 and comprises an arc shaped brake member 25 having upper and lower guide flanges 26 spaced apart a sufficient distance to permit the ring to rotate freely therebetween. This brake member 25 is lined with a frictional material such as leather, as shown at 27, which may engage the outer face of the traveler. For the purpose of supporting the brake in position relative to the traveler 2 a pair of adjacent outwardly extending lugs may be extended toward each other as shown at 30 in Figure 1, the top faces of these extensions forming supports on which end extensions 31 of the brake member 25 may ride. In order to provide for adjustably applying pressure to the brake member 25 to force it against the ring, means such as is shown in these figures may be employed comprising a spring bar 35 notched at its ends as at 36 (see Figure 2) to detachably engage the shanks of screws 37 beneath their heads, these screws being threaded into the supports 5. The mid length of the bar 35 has fixed thereto a block 38 through which is threaded a screw 39 bearing at its inner end against the outer face of the brake 25 and having at its outer end a knurled head 40 by which it may be turned. Interposed between the head 40 and the bar 35 is shown a lock nut 41 also threaded on the screw 39 and having an actuating disk or head 42 thereon preferably of slightly larger diameter than the head 40 to permit it to be readily actuated by the operator. By adjusting the position of the screw 39 relative to the spring 35 more or less pressure may be exerted against the brake 25 to thus apply more or less drag to the rotation of the ring traveler in addition to that caused by the small rollers 10. While one brake only is shown a plurality of brakes spaced about the periphery of the ring might, of course, be employed if desired.

Another form of brake is shown in Figures 6 and 7 and in which a brake element 50, flanged to project above and below the ring traveler is provided with a boss 51 perforated to receive a rock shaft 52 carrying at its upper end a head 53 by which it may be turned, this head resting on the upper face of the boss 51. The lower end of this rock shaft is of reduced diameter as shown at 54, this portion being arranged eccentrically to the remainder of the shaft. This portion is journaled in an eye 55 at one end of a leaf spring 56 which is made fast at its other end as at 57 to the support 1. By turning the head 53 the effective connection of the spring to the brake member 50 may be adjusted to and from the ring traveler so that the spring may press with a lighter or

heavier pressure thereon and consequently adjust the retarding effect produced by the brake. A set screw having a knurled head shown at 58 passes through the boss 51 and 5 engages the rock shaft 52 to fix the parts in any adjusted position.

In Figure 8 a further modification is shown in which the frictional face of the brake is furnished by a pair of rollers 60 10 journaled in opposite ends of the brake between its upper and lower flanges. These rollers are of small diameter so that they can not attain the peripheral speed of the ring traveler and therefore have a dragging 15 effect thereon.

The yarn eye, which as above noted, is positioned entirely within the ring traveler, is formed as shown more particularly in Figures 1 and 5 by means of a pair of hooks 20 70 and 71, each formed of a wire or pin having a reduced extremity as at 72 extending through perforations 73 spaced apart both horizontally and vertically in the inner face of the ring 20. These hooks 70 and 71 face each other, their free ends extending in opposite directions closely spaced past each other and being brought into close proximity with the inner face of the ring at the points 74 beyond which they are outwardly 25 turned as at 75. The yarn may be readily placed in position through the eye thus formed by bringing it first under the end 75 of the lower hook member, moving it toward the central portion of the member and then 30 bringing it over and putting it under the end 75 of the upper hook and then bringing it to the central position where it passes through the vertical opening 76 defined by the two hook elements and the inner face of 35 the ring. The elements 70 and 71 lie entirely between the planes of the upper and lower faces of the ring and hence are not liable to cause injury to the operator's fingers since they are entirely out of the way. 40 The construction also is readily threaded and when once threaded the yarns can not become accidentally unthreaded during the spinning or twisting operation.

Having thus described an embodiment of 45 this invention, it should be evident to those skilled in the art that many changes and modifications might be made therein without departing from its spirit or scope as defined by the appended claims.

50 I claim:

1. A device of the class described comprising a ring, and a plurality of flanged rollers spaced about the periphery of said ring in the same plane therewith and supporting the same for axial rotation between the flanges the flanges of said rollers projecting over and contacting with the faces of said ring.

2. A device of the class described comprising a ring mounted for rotation about its

axis, and a stationary brake acting on said ring for imparting a drag to the rotation thereof.

3. A device of the class described comprising a ring mounted for rotation about its axis, a stationary brake acting on said ring for imparting a drag to the rotation thereof, and means for effecting an adjustable pressure of said brake on said ring. 70

4. A device of the class described comprising a ring traveler, spaced bearings for supporting said traveler for axial rotation, and a brake member engageable with the outer periphery of said ring between a pair of adjacent bearings. 75

5. A device of the class described comprising a ring traveler, spaced bearings for supporting said traveler for axial rotation, a brake member engageable with the outer periphery of said ring between a pair of adjacent bearings, and means for adjusting the pressure of said brake against said traveler. 80 85

6. A device of the class described comprising a ring shaped support having spaced outwardly extending lugs, each lug having a lubricant-receiving socket extending from its upper face, a roller journaled in each socket and having its peripheral face positioned above said support, a ring traveler having its outer periphery in engagement with said roller faces, and a brake engageable with the outer periphery of said traveler between adjacent rollers. 90 95

7. A device of the class described comprising a ring shaped support having spaced outwardly extending lugs, each lug having a lubricant-receiving socket extending downwardly from its upper face, a roller journaled in each socket and having its peripheral face positioned above said support, a ring traveler having its outer periphery in engagement with said roller faces, and a brake engageable with the outer periphery of said traveler between adjacent rollers and supported at its ends on a pair of said lugs. 100 105

8. A device of the class described comprising a ring shaped support, spaced lugs extending from said support, bearing supports fixed to said lugs, bearings carried by said bearing supports, a ring traveler rotatably engaging on its outer face said bearings, a brake movable against the outer face of said ring traveler between a pair of adjacent bearing supports, a spring detachably engaging at its ends said pair of supports, and an adjusting screw threaded through said spring and engaging said brake for adjusting the pressure exerted by said brake against said traveler. 110 115 120

9. A device of the class described comprising a ring shaped support, spaced lugs extending from said support, bearing supports fixed to said lugs, bearings carried by said bearing supports, a ring traveler rotata- 125 130

bly engaging said bearings on its outer face, a brake movable against the outer face of said ring traveler between a pair of adjacent bearing supports and supported at opposite ends on said lugs, a spring detachably engaging at its ends said pair of supports, and an adjusting screw threaded through said spring and engaging said brake for adjusting the pressure exerted by said brake 10 against said traveler.

10. A device of the class described comprising a ring shaped support having spaced sockets about its periphery, a lubricant cup in each socket, a pivot carried by each support and projecting into the corresponding cup, a flange roller journaled on each pivot, a lubricant duct extending axially of each pivot and through which lubricant may be supplied to each cup, and a 20 ring traveler supported for axial rotation between the flanges of said rollers.

11. A device of the class described comprising a ring shaped support having spaced sockets about its periphery, a lubricant cup 25 in each socket, a pivot carried by each support and projecting into the corresponding cup, a flange roller journaled on each pivot, the peripheral face of said roller partially enclosing the open end of said cup, a lubricant duct extending axially of each pivot and through which lubricant may be supplied to each cup, and a ring traveler supported for axial rotation between the flanges 30 of said rollers.

35. 12. In a device of the class described, a support, a socket in the upper face of said support a bearing holder fixed to said support adjacent said socket and projecting thereover, a hollow shaft fixed to said projecting portion and extending into said socket, a roller having an elongated hub journaled on said shaft, said hub extending into said socket, the periphery of said roller overlying said support adjacent said socket, 40 and a ring traveler rotatable about said support and engaging said rollers on its outer face, said shaft being open at its upper end through which lubricant may be inserted 45 into said socket.

50. 13. In a device of the class described, a support, a socket in the upper face of said support, a bearing holder fixed to said sup-

port adjacent said socket and projecting thereover, a hollow shaft fixed to said projecting portion and extending into said socket, a roller having an elongated hub journaled on said shaft, said hub extending into said socket, the periphery of said roller overlying said support adjacent said socket, a ring traveler rotatable about said support 55 and engaging said rollers on its outer face, said shaft being open at its upper end through which lubricant may be inserted into said socket, and a cleaning passage extending downwardly from the upper face 60 of said support beneath said ring traveler and opening out through the outer face thereof.

14. A device of the class described comprising a ring, and a yarn eye having a 70 passage for the yarn within said ring.

15. A device of the class described comprising a ring, and a yarn eye carried on the inner face of said ring and below its upper surface.

16. A device of the class described comprising a ring, and a yarn eye carried on the inner face of said ring and lying entirely between the planes of its upper and lower surfaces.

17. In a device of the class described, a ring traveler, and a yarn eye projecting from the inner face of said traveler between its upper and lower faces, said eye comprising a pair of hooks fixed at one end to said traveler and spaced horizontally and vertically, said hooks lying in horizontal planes and facing each other to define with the inner face of said traveler a vertical opening for the yarn into which opening the yarn may be inserted by passing it alternating from opposite sides between the free ends of said hooks and the face of the traveler.

18. In a device of the class described, a 90 yarn eye for a ring traveler comprising a pair of pins fixed at one end to said traveler at spaced points, the opposite ends of said pins being bent past each other and spaced slightly from the face of said traveler and from each other.

In testimony whereof I have affixed my signature.

WILHO A. KOSKEN
